UNITED STATES PATENT OFFICE.

PLACID N. CHIASSON, OF GRIGGSVILLE, ILLINOIS.

DESIGN FOR A SPECTACLE FRAME.

Application filed September 29, 1924. Serial No. 10,926. Term of patent 14 years.

To all whom it may concern:

Be it known that I, PLACID N. CHIASSON, a citizen of the United States, residing at Griggsville, in the county of Pike and State of Illinois, have invented a new, original, and ornamental Design for Spectacle Frames, of which the following is a specification, reference being had to the accompanying drawing, forming part thereof.

In the drawing, Figure 1 represents in a perspective view a spectacle frame embodying my invention as in use, the head of the wearer being in dotted lines, and Figure 2 represents the frame in a side elevation.

I claim:

The ornamental design for a spectacle frame, as shown.

PLACID N. CHIASSON, M. D.
